UNITED STATES PATENT OFFICE.

GEORGE F. HAWLEY, OF SAN FRANCISCO, CALIFORNIA.

CALENDAR.

Application filed November 14, 1925. Serial No. 69,158.

To all whom it may concern:

Be it known that I, GEORGE F. HAWLEY, a citizen of the United States, and a resident of San Francisco, in the county of San Francisco and State of California, have invented a new and useful Improvement in Calendars, of which the following is specification.

This invention relates to calendars. An object of my present invention is the provision of a calendar by which may be readily determined the day of a week on which any predetermined day of the year falls.

With the foregoing object in view, together with such other objects as may subsequently appear, this invention resides in the construction and arrangement of parts hereinafter described and claimed, and illustrated in the accompanying drawings, in which—

Figure 1 is a plan view of my calendar comprising a disk, partly inscribed, and rotatably mounted on a back.

Figure 2 is a section taken on line 2—2 of Figure 1.

Figure 3 is a fragmentary plan view of my calendar provided with a slotted cover, and

Figure 4 is a view similar to Figure 3 showing a rotatable disk in a different position from that shown in Figure 3.

Referring to the drawings for more detailed description thereof, my calendar comprises a back 5 to which is secured a circular disk 6 which rises above the surface of the back 5 and a circular disk 7 has a central circular aperture cut therein, this aperture being of very slightly larger diameter than the disk 6. The disk 7 is placed on the back 5, the disk 6 protruding through the central aperture in the disk 7. The disk 6 is slotted diametrically to slidably receive an elongated indicator 9 having a triangular shaped end 10 and provide at its other end with a raised portion 11. The upper surface of the indicator 9 is flush with the upper surface of the disk 6. The indicator 9 is held in the slot of the disk 6 by a cross piece 12 secured to the disk 6. The rotatable disk 7 is marked with the numerals 1 to 31 inclusive, these numerals being arranged in a circle outside of the disk 6 and concentrically therewith. Outside of the numerals 1 to 31 inclusive and concentrically therewith, the disk 7 is marked with a series

of concentric circles in the spaces between which are written the days of the week. The slideable indicator is marked with the months of the year in the order in which they occur, beginning with January adjacent the triangular end portion of the indicator.

It will be noted from Figure 1 that when the indicator 9 is slidably disposed so that the portion bearing the word January lies over a part of the circle marked with the numerals and that when the disk 7 is rotated so that the numeral 1 is just to the right of January, the triangular portion 10 of the indicator points to Friday. This indicates that January the first of a certain year is on a Friday. It will be noted that if the disk 7 be rotated toward the left so that the numeral 2 lies just to the right of the space marked January, the indicator will point to the space marked Saturday, indicating that January the second falls on a Saturday.

It will thus be seen that the disk 7 is provided with a first series of spaces circularly arranged in which are successively written the names of the days of the week as they succeed each other, and that these week-day names are opposite the numerals indicating days of a month. In other words, if January the first is on a Friday, the spaces clockwise of the space in which Friday is written are labeled Saturday, Sunday, Monday, Tuesday, Wednesday, Thursday, Friday, Saturday, Sunday, etc. It will be seen that January 31st of the year for which my improved calendar is made up is on Sunday. When the indicator 9 is pushed upwardly so that the portion thereof bearing the mark February lies over a portion of the circle having numerals marked thereon, and the disk 7 is disposed so that the numeral 1 lies just to the right of the marking February, the triangular portion 10 of the indicator will point to Monday which is the day succeeding the Sunday of January 31st.

The second circle of days beginning with Monday is successively marked with the names of the days of the week in the order in which they occur. It will be noted, however, that the spaces marked *a*, *b* and *c* which are respectively opposite the numerals 28, 29 and 30 are left blank because no day should be indicated for February 29, 30 and 31 in the year for which the calendar is

made up which happens to be the year 1926, a non-leap year. It will be noted that February 28th is on a Sunday so that the third circle of days begins with Monday, each succeeding space of that circle being marked with the name of a week-day and the names following in their recognized sequence. A series of twelve successive circles formed by the names of the days of the week are thus written on the disk 7, the method for which will be readily apparent from the foregoing description.

It will be noted that in the radial column D the space e is left blank because there is no April 31st, and that the spaces f, g and h are also left blank because there is no June 31, September 31 nor November 31, the triangular end 10 of the indicator 9 being at the space e, f, g and h when the numeral 31 is to the right of April, June, September and November respectively.

In Figures 3 and 4 it will be noted that my calendar may comprise a cover 15 which may be secured to the back 5. The cover 15 is provided with a slot 16 which is wedge-shape. The slot 16 is provided for the purpose of exposing to view part of the pointer and a column marked with days of the week. A slot 16 is also cut to expose a numeral lying to the right of the space marked with the name of a month on the indicator. The cover 15 is also provided with a slot 17 so that the indicator which, as above mentioned, has a raised portion 11 at its lower end, may slide in its slot in the disk 6. The cover 15 is so cut at its bottom edge 18 that the disk 7 extends therebelow as shown in Figures 3 and 4, so that the disk may be grasped by the hand for turning.

Although I have shown and described one embodiment of my invention, it is to be understood that the same is susceptible of various changes; and I reserve the right to employ such as may come within the scope of the appended claims.

I claim:

1. A calendar comprising a rotatable disk having marked thereon in concentric circles the days of the week, said disk also having marked thereon the numerals from 1 to 31 inclusive, said numerals being circularly arranged and concentric with the circles in which the days of the week are arranged and an indicator movable longitudinally across said disk, said indicator having marked thereon the months of the year. 55

2. A calendar comprising a back, a disk rotatably mounted on said back, said disk having marked thereon the numerals from 1 to 31 inclusive, said numerals being circularly arranged and concentric with the circles in which the days of the week are arranged an indicator movable longitudinally across said disk, said indicator having marked thereon the months of the year, and a cover over said disk, said cover having an opening therein to expose to view a radial section of said disk bearing the days of the week and a part of said indicator bearing the months of the year. 65

3. A calendar comprising a back, a disk rotatably mounted on said back, said disk having marked thereon the numerals from 1 to 31 inclusive, said numerals being circularly arranged and concentric with the circles in which the days of the week are arranged, an indicator movable longitudinally across said disk, said indicator having marked thereon the months of the year, a cover over said disk secured to said back, 70 75 and a cover over said disk, said cover having an opening therein to expose to view a radial section of said disk bearing the days of the week and a part of said indicator bearing the months of the year, said cover also having an opening giving access to the lower part of said indicator so that the latter may be manually moved. 80 85

GEORGE F. HAWLEY.
